UNITED STATES PATENT OFFICE

ARCHIBALD I. MCCOLL, OF KALAMAZOO, MICHIGAN

TOILET SEAT

Application filed December 30, 1929. Serial No. 417,352.

The main objects of this invention are:

First, to provide a toilet seat in which portions thereof are covered with paper, the paper being automatically shifted by the raising and lowering of the seat.

Second, to provide a toilet seat with a sanitary cover for the supporting portions thereof which may be easily manipulated for the placing of fresh rolls of paper and the removal of used rolls.

Third, to provide a structure having these advantages which is very positive in operation, the seat covering paper being automatically fed without likelihood of its being fractured or broken.

Objects relating to details and economies of my invention will appear from the description to follow. The invention is defined and pointed out in the claims.

20. A structure which is a preferred embodiment of my invention is illustrated in the accompanying drawings, in which:

Fig. 1 is a plan view of my improved toilet seat.

25. Fig. 2 is a fragmentary view partially in section on a line corresponding to line 2—2 of Fig. 3.

Fig. 3 is a detail fragmentary transverse section on line 3—3 of Fig. 2.

30. Fig. 4 is an enlarged transverse section on line 4—4 of Figs. 1 and 2.

Fig. 5 is a detail section on line 5—5 of Figs. 1 and 2 showing details of the seat structure and the roll supports.

35. Fig. 6 is an end view of one of the removable side member top sections.

Fig. 7 is an enlarged detail section on line 7—7 of Figs. 1 and 2.

40. Fig. 8 is a perspective sectional view of one of the winding rolls illustrating the means for attaching the end of a web of paper thereto.

Referring to the drawings, 1 represents the bowl of a water closet and 2 the water supply connection.

My improved seat is of general U-shape facing forwardly, the side members converging as is clearly illustrated.

45. The rear or cross member 3 and also the side members 4 are chambered, being preferably

formed up of sheet metal which may be enamelled or finished as desired.

The side members have removable top sections 5 detachably retained by means of spring latches 6 engageable with keepers 7 within the bottom or fixed portion of the side members, the ends of the side members being slotted at 8 to receive a screw driver, coin or other object as indicated at 9 whereby these latches may be disengaged.

50. The top sections have projecting parts 10 at their rear ends engageable under the flange-like projections 11 so that it is only necessary to engage these lugs 10, push the forward ends of the top sections downwardly 55 until the catches engage with their keepers to effectively secure the top sections in position.

55. These top sections carry roll supports 12 and 13 at their rear ends and supports 14 at their forward ends with which the rolls 15 and 16 may be engaged, the roll 15 being the supply roll while the roll 16 is a winding roll. This winding roll is provided with a chuck engaging member 17 coacting with the driving means to be hereinafter described.

60. The seat is pivotally mounted on a pintle 18 carried by the posts 19 and 20 projecting through slots 21 in the bottom wall of the chambered rear member 3 of the seat, the seat having bearings 22 engaging the ends of this spindle.

65. The spindle is secured to the post 19 by means of the pin 23. A sleeve 24 on the spindle is rotatably mounted in the post 20, this sleeve being engaged by one end of the coiled spring 25 arranged on the spindle, the opposite end of this spring being engaged with the post 19.

70. The sleeve has a non-circular portion 26 with which the rear portion of the seat 27 engages so that the spring acts to swing the seat to upright position. A corresponding yoke 28 engages a fixed sleeve 29, this however being merely a matter of providing a support.

75. Segmental racks 30 are secured to the shaft by means of pins 31.

80. The driving shafts 32 are mounted in the supports 33 provided therefor in the side members of the seat (see Fig. 3), these shafts 85

60

55

60

65

70

75

80

85

95

100

having chucks 34 on their forward ends with which the chucks 17 engage when the top portion of the seat is in position as illustrated in Figs. 2 and 3.

5 Beveled pinions 35 are fixedly mounted on these shafts and provided with ratchet clutches 36 coacting with the ratchet clutch members 37 slidably mounted on the shaft to rotate therewith and held in yielding engagement with the pinion clutches 36 by means of the springs 38 so that as the seat is swung in one direction on its pivot, the shafts are driven to drive the winding roll a sufficient distance to present a fresh surface of the covering web of paper.

In the embodiment illustrated the rear ends of the shafts 32 are supported in bearings 39 rotatably mounted on the spindle 20. This provides an effective support for the shafts 20 and permits the swinging of the seat upon the spindle.

To facilitate the attachment of the web of paper 40 to the winding roll, the winding roll is provided with a resilient facing 41 upon suitable core, an attaching strip 42 being secured at one end to the winding roll so that the end of the web may be inserted between this attaching strip and wound up therewith, thereby frictionally holding the web.

The side members are provided with openings 43 at the sides thereof through which the web of paper may be passed from the winding roll over the inwardly inclined supporting surface of the side members of the seat, this supporting surface being preferably straight so that the web of paper lies flat thereon.

By thus protecting the surface of the seat, it may be formed of metal and enameled, thus presenting a very durable surface and at the same time a covered or protected surface.

My improvements enable the quick removal and replacement of the rolls; the paper is positively fed by the manipulation of the seat, that is, the raising and lowering thereof.

I have not attempted to illustrate or describe various modifications and adaptations which I contemplate as it is believed that this disclosure will enable those skilled in the art to embody or adapt my improvements as may be desired.

Having thus described my invention, what I claim as new and desire to secure by Letters Patent, is:

1. The combination of a forwardly facing U-shaped toilet seat having chambered rear and side members, the side members having removable top sections provided with roll holders, supply and winding rolls mounted in parallel relation in said holders, the winding rolls being provided with chuck engaging members at their rear ends, the seat side mem-

bers having slots in the sides thereof through which a web of paper may be passed from the supply rolls around the tops of the side members to the winding rolls, the side members having straight paper supporting portions, supporting posts, the bottom wall of the rear seat member having slots therein to receive said posts, a seat supporting spindle arranged in the rear seat member and keyed to one of said posts, a sleeve on said spindle rotatable in the other post and having a portion of non-circular cross section, bearings mounted in the rear member of said seat to coact with the said spindle whereby the seat is pivotally supported, a yoke mounted within the rear member of said seat in engagement with the non-circular portion of said sleeve, a coiled spring acting to swing the seat to raised position arranged on said spindle between said posts and connected at one end to the post to which the spindle is keyed and at the other end to said sleeve on said spindle, segmental racks keyed to said spindle, winding roll driving shafts mounted in the side members of the seat and provided with chucks with which the winding roll chuck engaging members are detachably engaged, bearings for the rear ends of said shafts rotatably mounted on said spindle, pinions rotatably mounted on said shafts to coact with said racks and provided with ratchet clutch members, and coacting ratchet clutch members rotatable with and yieldingly supported on said spindles to coact with said pinion clutches.

2. The combination of a forwardly facing U-shaped toilet seat having chambered rear and side members, supply and winding rolls mounted in parallel relation in said side members, the seat side members having slots in the sides thereof through which a web of paper may be passed from the supply rolls around the tops of the side members to the winding rolls, supporting posts, a seat supporting spindle arranged in the rear seat member and keyed to one of said posts, a sleeve on said spindle rotatable in the other post and having a portion of non-circular cross section, bearings mounted in the rear member of said seat to coact with the said spindle whereby the seat is pivotally supported, a yoke mounted within the rear member of said seat in engagement with the non-circular portion of said sleeve, a coiled spring acting to swing the seat to raised position arranged on said spindle between said posts and connected at the other end of said sleeve on said spindle, segmental racks keyed to said spindle, winding roll driving shafts, bearings for the rear ends of said shafts rotatably mounted on said spindle, pinions rotatably mounted on said shafts to coact with said racks and provided with ratchet clutch members, and coacting ratchet clutch members rotatable with and yieldingly supported on said spindles to coact with said pinion clutches.

3. The combination of a forwardly facing U-shaped toilet seat having chambered rear and side members, the side members having removable top sections provided with roll holders, supply and winding rolls mounted in parallel relation in said holders, the winding rolls being provided with chuck engaging members at their rear ends, the seat side members having slots in the sides thereof through which a web of paper may be passed from the supply rolls around the tops of the side members to the winding rolls, a seat supporting spindle arranged in the rear seat member, a sleeve on said spindle connected to said seat, bearings on said seat coacting with the said spindle whereby the seat is pivotally supported, a coiled spring acting to swing the seat to raised position arranged on said spindle and connected at one end to a fixed part and at the other end to said sleeve on said spindle, segmental racks, winding roll driving shafts mounted in the side members of the seat and provided with chucks with which the winding roll chuck engaging members are detachably engaged, pinions rotatably mounted on said shafts to coact with said racks and provided with ratchet clutch members, and coacting ratchet clutch members rotatable with and yieldingly supported on said spindles to coact with said pinion clutches. 70
- 5 10 15 20 25 30 35 40 45 50 55 60 65 70 75 80 85 90 95 100 105 110 115 120 125 130
4. The combination of a forwardly facing U-shaped toilet seat having chambered rear and side members, supply and winding rolls mounted in parallel relation in said seat, the seat side members having slots in the sides thereof through which a web of paper may be passed from the supply rolls around the tops of the side members to the winding rolls, a seat supporting spindle arranged in the rear seat member, a sleeve on said spindle connected to said seat, bearings on said seat coacting with the said spindle whereby the seat is pivotally supported, a coiled spring acting to swing the seat to raised position arranged on said spindle and connected at one end to a fixed part and at the other end to said sleeve on said spindle, segmental racks, winding roll driving shafts, pinions rotatably mounted on said shafts to coact with said racks and provided with ratchet clutch members, and coacting ratchet clutch members rotatable with and yieldingly supported on said spindles to coact with said pinion clutches. 95
3. The combination of a forwardly facing U-shaped toilet seat having chambered rear and side members, supply and winding rolls mounted in parallel relation in said side members, the seat side members having slots in the sides thereof through which a web of paper may be passed from the supply rolls around the tops of the side members to the winding rolls, a seat supporting spindle arranged in the rear seat member and keyed to one of said posts, bearings mounted in the rear member of said seat to coact with the said spindle whereby the seat is pivotally supported, segmental racks keyed to said spindle, winding roll driving shafts, bearings for the rear ends of said shafts rotatably mounted on said spindle, pinions rotatably mounted on said shafts to coact with said racks and provided with ratchet clutch members, and coacting ratchet clutch members rotatable with and yieldingly supported on said spindles to coact with said pinion clutches. 100
4. The combination of a forwardly facing U-shaped toilet seat having chambered rear and side members, supply and winding rolls mounted in parallel relation in said side members, the seat side members having slots in the sides thereof through which a web of paper may be passed from the supply rolls around the tops of the side members to the winding rolls, a seat supporting spindle arranged in the rear seat member and keyed to one of said posts, bearings mounted in the rear member of said seat to coact with the said spindle whereby the seat is pivotally supported, segmental racks keyed to said spindle, winding roll driving shafts, bearings for the rear ends of said shafts rotatably mounted on said spindle, pinions rotatably mounted on said shafts to coact with said racks and provided with ratchet clutch members, and coacting ratchet clutch members rotatable with and yieldingly supported on said spindles to coact with said pinion clutches. 105
5. The combination of a forwardly facing U-shaped toilet seat having chambered rear and side members, the side members having removable top sections provided with roll holders, supply and winding rolls mounted in parallel relation in said holders, the winding rolls being provided with chuck engaging members at their rear ends, the seat side members having slots in the sides thereof through which a web of paper may be passed from the supply rolls around the tops of the side members to the winding rolls, a seat supporting spindle arranged in the rear seat member, bearings on said seat coacting with the said spindle whereby the seat is pivotally supported, segmental racks, winding roll driving shafts mounted in the side members of the seat and provided with chucks with which the winding roll chuck engaging members are detachably engaged, pinions rotatably mounted on said shafts to coact with said racks and provided with ratchet clutch members, and coacting ratchet clutch members rotatable with and yieldingly supported on said spindles to coact with said pinion clutches. 110
6. The combination of a forwardly facing U-shaped toilet seat having chambered rear and side members, supply and winding rolls mounted in parallel relation in said seat, the seat side members having slots in the sides thereof through which a web of paper may be passed from the supply rolls around the tops of the side members to the winding rolls, a seat supporting spindle arranged in the rear seat member, a sleeve on said spindle connected to said seat, bearings on said seat coacting with the said spindle whereby the seat is pivotally supported, a coiled spring acting to swing the seat to raised position arranged on said spindle and connected at one end to a fixed part and at the other end to said sleeve on said spindle, segmental racks, winding roll driving shafts, pinions rotatably mounted on said shafts to coact with said racks and provided with ratchet clutch members, and coacting ratchet clutch members rotatable with and yieldingly supported on said spindles to coact with said pinion clutches. 115
7. The combination of a forwardly-facing U-shaped toilet seat having chambered rear and side members, the side members having removable top sections provided with roll holders, supply and winding rolls mounted in parallel relation in said holders, the winding rolls being provided with chuck engaging members at their rear ends, the seat side members having slots in the sides thereof through which a web of paper may be passed from the supply rolls around the tops of the side members to the winding rolls, a seat supporting spindle arranged in the rear seat member, bearings on said seat coacting with the said spindle whereby the seat is pivotally supported, segmental racks, winding roll driving shafts mounted in the side members of the seat and provided with chucks with which the winding roll chuck engaging members are detachably engaged, pinions rotatably mounted on said shafts to coact with said racks and provided with ratchet clutch members, and coacting ratchet clutch members rotatable with and yieldingly supported on said spindles to coact with said pinion clutches. 120
8. The combination of a forwardly-facing U-shaped toilet seat having chambered rear and side members, the side members having removable top sections provided with roll holders, supply and winding rolls mounted in parallel relation in said holders, the winding rolls being provided with chuck engaging members at their rear ends, the seat side members having slots in the sides thereof through which a web of paper may be passed from the supply rolls around the tops of the side members to the winding rolls, a seat supporting spindle arranged in the rear seat member, bearings on said seat coacting with the said spindle whereby the seat is pivotally supported, segmental racks, winding roll driving shafts mounted in the side members of the seat and provided with chucks with which the winding roll chuck engaging members are detachably engaged, pinions rotatably mounted on said shafts to coact with said racks and provided with ratchet clutch members, and coacting ratchet clutch members rotatable with and yieldingly supported on said spindles to coact with said pinion clutches. 125

bers are detachably engaged, pinions rotatably mounted on said shafts to coact with said racks and provided with ratchet clutch members, and coacting ratchet clutch members 5 rotatable with and yieldingly supported on said spindles to coact with said pinion clutches.

8. The combination of a forwardly facing U-shaped toilet seat having chambered rear 10 and side members, supply and winding rolls mounted in parallel relation in said seat, the seat side members having slots in the sides thereof through which a web of paper may be passed from the supply rolls around the 15 tops of the side members to the winding rolls, a seat supporting spindle arranged in the rear seat member, bearings on said seat coacting with the said spindle whereby the seat is pivotally supported, segmental racks, winding roll driving shafts, pinions rotatably mounted on said shafts to coact with said racks and provided with ratchet clutch members, and coacting ratchet clutch members 20 rotatable with and yieldingly supported on said spindles to coact with said pinion clutches.

9. The combination of a chambered toilet seat, the side portions of which are substantially straight and having removable top sections, each provided with supply and winding roll holders, supply and winding rolls mounted in said holders, the winding rolls being provided with chuck engaging members, the seat side members having slots 30 therein through which a web of paper may be passed from the supply rolls over the tops of the side members to the winding rolls, a supporting spindle on which said seat is pivotally mounted, a sleeve rotatable on said 35 spindle, a coiled spring arranged on said spindle, one edge of the spring being engaged with the sleeve and the other with a non-rotatable part whereby the spring acts 40 to swing the seat to raised position, segmental racks keyed to said spindle, winding roll driving shafts mounted within said seat and provided with chucks with which the winding roll chuck engaging members are detachably engageable, pinions rotatably mounted 45 on said shafts to coact with said racks and provided with ratchet clutch members, and coacting ratchet clutch members rotatable with and yieldingly supported on said spindles to coact with said pinion clutches.

50 10. The combination of a chambered toilet seat, supply and winding rolls mounted in said seat, the seat side members having slots therein through which a web of paper may be passed from the supply rolls over the 55 tops of the side members to the winding rolls, a supporting spindle on which said seat is pivotally mounted, a sleeve rotatable on said spindle, a coiled spring arranged on said spindle, one edge of the spring being engaged with the sleeve and the other with a

non-rotatable part whereby the spring acts to swing the seat to raised position, segmental racks keyed to said spindle, winding roll driving shafts mounted within said seat, pinions rotatably mounted on said shafts to 70 coact with said racks and provided with ratchet clutch members, and coacting ratchet clutch members rotatable with and yieldingly supported on said spindle to coact with said pinion clutches. 75

11. The combination of a chambered toilet seat, the side portions of which are substantially straight and having removable top sections, each provided with supply and winding roll holders, supply and winding rolls mounted in said holders, the winding rolls being provided with chuck engaging members, the seat side members having slots therein through which a web of paper may be passed from the supply rolls over the tops of the side members to the winding rolls, a supporting spindle on which said seat is pivotally mounted, a sleeve rotatable on said spindle, segmental racks keyed to said spindle, winding roll driving shafts mounted 80 within said seat and provided with chucks with which the winding roll chuck engaging members are detachably engageable, pinions rotatably mounted on said shafts to coact with said racks and provided with ratchet clutch members, and coacting ratchet clutch members rotatable with and yieldingly supported on said spindle to coact with said pinion clutches. 85

12. The combination of a chambered toilet seat, supply and winding rolls mounted in said seat, the seat side members having slots therein through which a web of paper may be passed from the supply rolls over the tops of the side members to the winding rolls, a supporting spindle on which said seat is pivotally mounted, a sleeve rotatable on said spindle, segmental racks keyed to said spindle, winding roll driving shafts mounted within said seat, pinions rotatably mounted 100 on said shafts to coact with said racks and provided with ratchet clutch members, and coacting ratchet clutch members rotatable with and yieldingly supported on said spindles to coact with said pinion clutches. 105

13. The combination of a chambered pivotally supported toilet seat, the side portions of which are substantially straight and provided with removable top sections, each having pairs of roll holders thereon, supply and winding rolls mounted on said supports, the seat side members having openings therein through which a web of paper may be passed from the supply rolls around the tops of the seat side members and to the winding rolls, a spring acting to raise said seat on its pivot, racks, winding roll driving shafts provided with chucks with which the winding roll chuck engaging members are detachably engageable, pinions rotatably mounted on said 110 120 125 130

shafts to coat with said racks as the seat is swung on its pivot, and a ratchet connection for said pinions to said shafts.

14. The combination of a chambered pivotally supported toilet seat having a removable top, supply and winding rolls mounted on said top within the seat, the seat side members having openings therein through which a web of paper may be passed from the supply rolls around the tops of the seat side members and to the winding rolls, a spring acting to raise said seat on its pivot, racks, winding roll driving shafts, pinions rotatably mounted on said shafts to coat with said racks as the seat is swung on its pivot, and a ratchet connection for said pinions to said shafts.

15. The combination of a chambered pivotally supported toilet seat, the side portions of which are substantially straight and provided with removable top sections, each having pairs of roll holders thereon, supply and winding rolls mounted on said supports, the seat side members having openings therein through which a web of paper may be passed from the supply rolls around the tops of the seat side members and to the winding rolls, racks, winding roll driving shafts provided with chucks with which the winding roll chuck engaging members are detachably engageable, pinions rotatably mounted on said shafts to coat with said racks as the seat is swung on its pivot, and a ratchet connection for said pinions to said shafts.

35 16. The combination of a chambered pivotally supported toilet seat having a removable top, supply and winding rolls mounted on said top within the seat, the seat side members having openings therein through which a web of paper may be passed from the supply rolls around the tops of the seat side members and to the winding rolls, racks, winding roll driving shafts, pinions rotatably mounted on said shafts to coat with said racks as the seat is swung on its pivot, and a ratchet connection for said pinions to said shafts.

17. The combination of a pivotally mounted toilet seat having a removable top and chambered substantially straight side portions, supply and winding rolls mounted on said top within said side portions, the said side portions having openings at the sides thereof through which a web of paper may be passed from the supply rolls around the tops of the side members to the winding rolls, a spring acting to raise said seat on its pivot, pinions having ratchet connection with the winding rolls, and racks with which said pinions coat as the seat is swung on its pivot.

60 18. The combination of a pivotally mounted toilet seat having a removable top and chambered side portions, supply and winding rolls mounted on said top within said side portions, the said side portions having openings at the sides thereof through which a web of

paper may be passed from the supply rolls around the tops of the side members to the winding rolls, a spring acting to raise said seat on its pivot, pinions having ratchet connection with the winding rolls, and racks with which said pinions coat as the seat is swung on its pivot.

19. The combination of a pivotally mounted toilet seat having a removable top and chambered substantially straight side portions, supply and winding rolls mounted on said top within said side portions, the said side portions having openings at the sides thereof through which a web of paper may be passed from the supply rolls around the tops of the side members to the winding rolls, pinions having ratchet connection with the winding rolls, and racks with which said pinions coat as the seat is swung on its pivot.

20. The combination of a pivotally mounted toilet seat having a removable top and chambered side portions, supply and winding rolls mounted on said top within said side portions, the said side portions having openings at the sides thereof through which a web of paper may be passed from the supply rolls around the tops of the side members to the winding rolls, pinions having ratchet connection with the winding rolls, and racks with which said pinions coat as the seat is swung on its pivot.

21. The combination of a pivotally mounted toilet seat having a chambered straight side portion provided with a removable top, said top having pairs of roll holders thereon, the side member having slots in the side walls thereof through which a web of paper may be passed from the supply rolls around the top section of the side member, winding and supply rolls arranged in said holders, and a winding roll driving means with which the winding roll is brought into driving relation when the removable top section is positioned on the seat.

In witness whereof I have hereunto set my hand.

ARCHIBALD I. McCOLL.
